UNITED STATES PATENT OFFICE.

CHARLES J. T. BURCEY, OF BINGHAMTON, NEW YORK.

APPARATUS FOR DISTILLING WOOD, &c.

SPECIFICATION forming part of Letters Patent No. 245,936, dated August 23, 1881.

Application filed April 19, 1881. (No model.)

To all whom it may concern:

Be it known that I, CHARLES J. T. BURCEY, of Binghamton, in the county of Broome and State of New York, have invented an Improvement in Apparatus for Distilling Wood, &c., of which the following is a specification.

My invention relates to that class of apparatus used for distilling wood in the manufacturers of wood-spirit, pyroligneous acid, tar, &c., and has for its object to uniformly heat the retorts throughout their entire extent, prevent overheating or burning, facilitate access to the fire-place for repairs, and economize fuel.

In the drawings, Figure 1 is a transverse sectional elevation of a wood-distilling apparatus illustrating my invention; Fig. 2, a section on line 1 2, Fig. 1; and Fig. 3, a section on the line 3 4, Fig. 1.

W represents a stack of masonry, in which are built a central longitudinal chamber, X, and two cylindrical chambers, Y, on opposite sides of the chamber X, and two longitudinal flues, V V, parallel to the chamber X, and communicating through vertical branches a with the chambers Y, and a rear cross-flue, G, connecting the flues V V and communicating with a suitable uptake.

In each chamber Y, concentric therewith, but smaller in diameter, so as to leave a surrounding flue, b, is a cylindrical vessel, K, the front end of which is provided with a door, M, and the rear end of which communicates through a pipe, d, with one or more condensers, N N, of any suitable shape, a pipe, f, discharging the liquid matter from the condensers, and a pipe, g, forked at the lower end, communicating with the top of the pipe f, and extending through the front wall into the chamber X above a grate, h, which divides said chamber into a fire-place, L, and ash-pit H. The side walls, p p, of the chamber X are in contact each with the adjacent side of the adjacent vessel K, and in an arch, E, sprung across these walls over the fire-place, and abutting on said vessels, are openings 1 to 8, formed by leaving out intermediate bricks. (See Figs. 2 and 3.)

The fire-place and ash-pit, as well as the flues V V, are provided with doors. There are also openings in the front wall, closed by covers, through which the opposite flues and spaces may be cleaned, while a central opening, pro-

vided with a suitable cover, permits the fire-place to be inspected during the distilling operations.

In the branch flues a are dampers F, which may be turned by handles projecting through the front wall. The pipe g terminates in a tube, w, into which projects a tube, u, communicating with a pipe, q, leading to a tar-vat, and into the tube u extends a small pipe, s, that communicates with a pipe, k, through which steam or air under pressure is supplied. The end of the pipe s terminates in a rose, or being finely perforated.

The wood or other matter to be distilled is introduced into the vessels K, a fire is kindled in the fire-place, and the dampers F turned so as to cause the incandescent gases to pass through the openings 1 to 8 and annular flues Y, round the vessels, and thence through the branches a and flues V G to the uptake.

Owing to the construction of the parts described, the gases will almost completely encircle the receptacles K, but so slowly as to impart the greater portion of their heat to the same, thereby producing a uniform temperature throughout the whole extent, but without bringing the flame directly in contact with the vessels, thereby preventing any burning of the latter. The acid and spirit are condensed and flow through the pipes f as liquids; but the gaseous matter will flow back through the pipe g to the fire-place, where it is forced forward by the jet of steam or air and intimately combined with the latter, and, if necessary, with a supply of tar, the whole forming a mixture which in burning will afford a large volume of hot gas, and as long as the distillation is continued constitutes the main supply of fuel.

Each pipe g q k has a cock to regulate the supply passing through the same.

By adjusting the dampers F the flow of gas and heat imparted to the receptacles may be readily regulated, thereby insuring such a steady and uniform action as will enable me to secure more acid with less tar and gas than by the apparatus commonly employed.

By springing the arch over the chamber X and abutting it on the vessels K the portion of masonry above the chamber X may be readily removed without breaking down the arches above the chambers Y.

Although I have shown but two receptacles,

any desired number may be placed side by side, using but one main flue to the whole, and one chamber, X, to each pair of receptacles. While the gases from the pipe *g* may be 5 passed directly from the said pipe and burned at the end of the latter, I prefer a burner something of the form described, as the forcing in of the gas by the steam or air tends to create a partial vacuum in the condensers, and 10 aids the distillation. Owing to the uniform steady but mild heat thus obtained, a better grade of charcoal is produced, while the whole process is economical and easily carried out.

I do not claim, broadly, injecting oil by means 15 of air or steam under pressure, nor burning the lighter products of distillation, as these are old; but by the combination described by me I am enabled to use both the waste gas and the waste tarry products. Nor do I here 20 claim the burner for burning oil and tar, as this may form the subject of a separate application for Letters Patent.

I claim—

1. In an apparatus for distilling wood, a stack having a central fire-place between cylindrical 25 chambers containing vessels K, flues *b*, communicating with the fire-place near the top and nearly surrounding said vessels, and flues *V*, parallel to and below said vessels and communicating with said chambers through branches 30 *a*, all as set forth.

2. The combination, in the stack, of the walls *p p*, inclosing the central fire-chamber, X, side chambers, Y Y, vessels K, arranged therein, arch E over the chamber X, abutting on said 35 vessels, and flues 1 to 8, forming a connection between the chambers X and Y, as set forth.

In testimony whereof I have signed my name to this specification in the presence of two subscribing witnesses.

CHARLES JOSEPH THÉOPHILE BURCEY.
